Clara T. Dame

HIS ATTORNEY

UNITED STATES PATENT OFFICE.

CLIVE W. LANPHERE, OF NEW YORK, N. Y.

DISPENSING DEVICE FOR GRANULAR MATERIALS.

Application filed June 27, 1923. Serial No. 648,026.

To all whom it may concern:

Be it known that I, CLIVE W. LANPHERE, a citizen of the United States, and a resident of New York, in the county and State of New York, have invented certain new and useful Improvements in Dispensing Devices for Granular Materials; and he does hereby declare the following to be a full, clear, and exact description of the invention, such as will enable others skilled in the art to which it appertains to make and use the same.

In a pending application filed by me July 1, 1922, Serial No. 572,120, there is disclosed a device for containing and dispensing granular materials, such as sugar, which comprises a magazine having one or more sockets, each provided with an inlet opening from the magazine chamber and an outlet opening; a measuring spindle rotatably fitted in each of the sockets and having a pocket which is shiftable, upon rotation of the spindle, from the inlet opening to the outlet opening; a stirring spindle in the magazine chamber for keeping the granular material in a loosened condition to insure its ready discharge from the magazine; and a removable cover for the magazine having openings through which the upper ends of the spindles project to be grasped and operated by the user.

In the device of my aforesaid application, the stirring and measuring spindles are loosely seated in the magazine without the employment of any means for locking them in position, and it has been found in practice that this method of assembling the parts is objectionable in that the spindles become readily displaced, and therefore liable to loss, in the ordinary handling of the devices. This displacement is particularly objectionable in the case of the measuring spindles, as any upward displacement of these from their seats permits the contents of the magazine to flow or leak outwardly under the same and so become lost. As to the stirring spindle, any upward displacement of this from its seat tends to interfere with its proper operation because of the sugar or other material in the magazine becoming lodged beneath the same. It has therefore been one of the objects of my present invention to provide a means for locking the spindles in operative connection with the magazine, and which means

will be of a character to permit of the ready assembling of the parts, and also of their ready disassembling for cleaning and like purposes.

A further object of my present invention is the provision of means for effecting a uniform distribution of the material over a somewhat extended area as it is discharged from the device, thereby making the latter especially useful in dispensing sugar directly on fruit, cereals, etc., which are served in relatively wide shallow dishes.

These objects, and others to be later referred to, are attained by the novel features of construction and combinations of parts hereinafter described and claimed, and which are illustrated in the accompanying drawings, in which,

Fig. 1 is a top plan view of a dispensing device embodying my invention;

Fig. 2, a side elevation of the device;

Fig. 3, a central vertical section of the device, taken on the line 3—3 of Fig. 1;

Fig. 4, an inverted plan view of the cover removed from the magazine;

Fig. 5, a sectional detail showing the locking connection between one of the measuring spindles and the magazine, the section being taken on line 5—5 of Fig. 2;

Figs. 6, 7 and 8 are details of a cover locking means to be hereinafter referred to.

To explain in detail, 10 indicates the body of the magazine, which is generally cylindrical in form and mounted on a supporting base 11. This magazine may be provided with one or more measuring and dispensing devices, the same in the present instance being provided with four. As these are all of like construction and operation, a detailed description of one will suffice for all.

Each measuring and dispensing device comprises a vertically arranged cylindrical socket 15 formed in the side of the magazine and having an inlet opening 16 at its lower end communicating with the magazine chamber 12, and an oppositely arranged outlet or discharge opening 17. Loosely fitted in this socket for rotative movement is a spindle 18 having formed in one side thereof a pocket 19 which is adapted to be shifted, by a rotative movement of the spindle, from a position opposite the inlet opening where it will receive the material in the magazine chamber, to a position opposite the outlet opening where it

will discharge such material. In this way the material contained in the magazine chamber, such as sugar, may be dispensed directly therefrom in measured quantities without the use of spoons or other like utensils, and the quantities dispensed may be regulated as desired simply by varying the size or capacity of the pocket 19 in the spindle.

10 As a means for keeping the granular material in the magazine in a loosened condition whereby it will flow freely through the openings 16 in its side walls and fill the pockets in the spindles 18, I provide a stirring spindle 20 which is mounted in the magazine chamber on a centrally located bearing post 21 and provided with laterally projecting stirring arms or blades 22. This stirring spindle 20, and also the measuring and dispensing spindles 18, all project at their upper ends, as at 23, through openings in the removable magazine cover 25, where they may be readily grasped and operated by the user.

25 As hereinbefore stated, it has been found desirable to lock the several spindles in connection with the magazine to prevent their accidental withdrawal or disconnection therefrom, and in doing this, it is desirable that the means for effecting locking connection should be such as to permit of the ready disconnection of the spindles for cleaning and like purposes. The means for so locking the stirring spindle in connection with the magazine comprises an inwardly turned locking finger 30 at the lower end of the spindle engaging an annular overhanging shoulder 31 on the bearing post 21, as shown in Fig. 3, this means acting to hold the spindle against withdrawal from the magazine while permitting of its rotation on the bearing post 21.

As shown in Fig. 3, the upper end of the bearing post 21 is made convex and the lower end of the spindle is made correspondingly concave, so as to form a socket-like joint between the parts. This prevents lateral displacement of the lower end of the spindle on the post 21 when held vertically in connection with the latter by the locking finger 30. To effect disconnection of the spindle from the post 21, the spindle must be tilted at an angle to the vertical to thereby shift its locking finger from beneath the shoulder 31, as shown by dotted lines in Fig. 3, in which position it is free to be withdrawn from the magazine. This tilting of the spindle can only be effected by removing the cover from the magazine and so freeing the upper end of the spindle. To replace the spindle in locking connection with the post 21, it is of course only necessary to reverse the order of operation followed in removing it. With such locking means, it will be

70 moved for cleaning and other like purposes, and that when it is connected with the bearing post and the cover placed in position, it will be positively locked in its operative connection with the magazine.

I will next describe the means for locking the measuring and dispensing spindles 18 within their containing sockets 15. This comprises a pin 40 on the inner wall of the socket engaging an annular shoulder 41 on the spindle, which shoulder is formed by a peripheral groove 42 on the said spindle. As a means for bringing said shoulder and pin into locking relation, the spindle is formed with a longitudinal groove 43 extending from its lower end to a point intersecting the annular groove 42, through which the pin is passed to permit lowering of the spindle into its socket. After the spindle has been seated and its shoulder 41 brought to a position beneath the plane of the pin 40, it is then given a partial rotation to bring said shoulder beneath the pin, as clearly shown in Fig. 5, thereby locking the spindle against withdrawal from its socket.

90 The spindle is limited in its rotative movement, when the cover is removed from the magazine, by means of a lug 44 thereon engaging with stop shoulders 45, 45', at the upper end of the spindle containing socket. These shoulders, in accordance with the present invention, are located sufficiently far apart to permit of a rotative movement of the spindle in excess of its normal movement in shifting its receiving pocket 19 from the inlet opening of the socket to the outlet opening. This excess movement of the spindle is for the purpose of permitting the longitudinal groove 43 therein being 100 brought into registry with the pin 40 for the release of the spindle, at a point beyond the limit of movement of the spindle in its normal operation. With this arrangement of the parts, after the spindle has been seated in its socket and given a partial rotation to bring its shoulder 41 beneath the pin 40, the cover is placed on the magazine and this is provided with a lug 47 on its under side which is positioned adjacent the shoulder 45', as clearly shown in Figs. 1 and 2, and acts to so limit the rotative movement of the spindle in a direction toward the pin 41 as to prevent its groove 43 being 110 brought into registry with said pin. It 115 will thus be understood that when the cover is on the magazine, its lugs 47 will cooperate with the lugs 44 on the spindles in a manner to maintain the latter in locked connection with the magazine, and upon the removal of the cover to withdraw its lugs from position for engagement with the spindle lugs, the spindles are then free to be given the additional turning movement necessary to bring their longitudinal grooves into reg- 120 125 130

istry with the locking pins and so permit the removal of the spindles from their sockets.

The several spindles, as described, are maintained in locked connection with the magazine through the instrumentality of the cover. If the latter becomes accidentally removed, the spindles are free to be released from their locked connection with the magazine. It may therefore be desirable, in some uses of the device, to lock the cover in place in order to maintain the locked connection of the spindles. As a simple and effective means for doing this, I provide one of the spindles—in the present case the central stirring spindle—with a collar 50 detachably locked thereon in position for engaging the top of the cover, and serving, because of the locked connection of the lower end of the spindle with the magazine, to lock the cover in place. As a means for effecting the ready connection of this collar 50 with the spindle, and its disconnection therefrom, I provide the collar with one or more inwardly projecting lugs 51 (Fig. 7) for engaging the spindle within an annular groove 52 therein (Fig. 8), the spindle being formed with vertical grooves 53 extending from the upper end of the spindle to said annular groove, through which the lugs 51 on the collar are passed in placing the collar in connection with the spindle or removing it therefrom. When the collar is placed on the spindle and given a partial turn to enter its lugs into the groove 52 for locking connection with the spindle, it is adapted to be retained in such position by a locking member 55 (Fig. 6), of inverted U-shape, which is placed on the upper end of the spindle with its opposite arms extending downwardly through the grooves 53 into the annular groove 52, where its ends will engage the lugs 51 of the collar 50 and prevent the same being brought to releasing position in registry with the vertical grooves 53. It will of course be obvious that this same cover locking means may also be applied to the measuring spindles 18 if so desired, or be applied to one or more of the latter instead of to the stirring spindle as shown.

As hereinbefore referred to, it is desirable in some instances to effect a uniform distribution of the material directly from the magazine over a somewhat extended surface, as in the spreading of sugar on fruit, cereals, etc. To accomplish this I provide the magazine with a perforated spreader 60 which flares outwardly and downwardly from the magazine at the lower end of the outlet opening 17 as shown, this spreader preferably being formed with its upper surface convex in a direction transversely thereof and terminating in a lower edge of substantially semi-circular form. This par-

ticular design of spreader has been found in practice to be most effective in causing a uniform spreading of the granular materials deposited thereon by the dispensing spindles.

The magazine may be provided with any desired number of dispensing spindles. In the present case, it is provided with two pairs arranged at opposite sides thereof with intervening handles 55. Each pair as shown includes one dispensing device with an associated spreader, and one dispensing device without a spreader, the latter device being intended more particularly for dispensing sugar directly into a coffee or tea cup where it is not necessary to spread the sugar, and the former being intended, as stated, for dispensing sugar on fruit, cereals, etc., where it is desirable that the sugar should be spread.

What I claim is:

1. A dispensing device for granular materials, comprising a magazine having an outlet opening in its side wall and a bearing post on its bottom wall provided with an undercut annular shoulder, a cover for the magazine having an opening, and a rotatable stirring spindle resting at its lower end on the bearing post and having its upper end projecting through the opening in the cover as a means whereby it may be operated, the said spindle being provided with a locking finger loosely engaging the annular shoulder on the bearing post to lock the spindle against withdrawal from the magazine when the cover is in place.

2. A dispensing device for granular materials, comprising a magazine having an outlet opening in its side wall and a bearing post on its bottom wall provided with an undercut annular shoulder, a rotatable stirring spindle resting on the bearing post, the said spindle and the post being provided, one with a concave surface forming a socket and the other with a convex surface fitting said socket, and the spindle also being provided with a locking finger cooperating with the annular shoulder on the post to lock the spindle vertically on the latter, and a cover for the magazine having an opening through which the spindle extends at its upper end to be maintained in locking connection with the bearing post.

3. A dispensing device for granular materials, comprising a magazine having a socket provided with an inlet opening from the magazine and an outlet opening, a measuring spindle rotatably fitted in said socket and having a pocket shiftable, upon rotation of the spindle, from the inlet opening to the outlet opening, and a perforated spreader positioned to receive the material from the outlet opening and effect a spreading of the same.

4. A dispensing device for granular ma-

aterials, comprising a magazine having a socket provided with an inlet opening from the magazine and an outlet opening, a measuring spindle rotatably fitted in said socket and having a pocket shiftable, upon rotation of the spindle, from the inlet opening to the outlet opening, and a spreader positioned to receive the material from the outlet opening and having an upper rounded 10 surface to effect a spreading of the material received thereon.

5. A dispensing device for granular materials, comprising a magazine having a socket provided with an inlet opening from the magazine and an outlet opening, a measuring spindle rotatably fitted in said socket and having a pocket shiftable, upon rotation of the spindle, from the inlet opening to the outlet opening, and a spreader 15 positioned to receive the material from the outlet opening and having a downwardly inclined surface which is convex in a direction transversely thereof.

20. 6. A dispensing device for granular materials, comprising a magazine having a socket provided with an inlet opening from the magazine and an outlet opening, a measuring spindle rotatably fitted in said socket and having a pocket shiftable, upon rotation of the spindle, from the inlet opening to the outlet opening, and a perforated 25 spreader positioned to receive the material from the outlet opening and having a downwardly inclined surface which is convex in a direction transversely thereof.

7. A dispensing device for granular materials, comprising a magazine having a socket provided with an inlet opening from the magazine and an outlet opening, a measuring spindle rotatably fitted in said socket and having a pocket shiftable, upon rotation of the spindle, from the inlet opening to the outlet opening, and a perforated spreader flaring outwardly and downwardly from the device at the discharge end of the outlet opening and terminating in an edge of 40 semi-circular form.

50. 8. A dispensing device for granular materials, comprising a magazine having a vertical socket at one side thereof provided with an inlet opening from the magazine and an outlet opening, a measuring spindle rotatably fitted in said socket and having a pocket shiftable, upon rotation of the spindle, from the inlet opening to the outlet opening, a removable cover for the magazine having an opening through which the upper end of the spindle extends, means engaging the spindle and holding it in its 55 socket during a fixed movement of rotation, and means carried by the removable cover for confining the spindle to said fixed movement of rotation.

60. 9. A dispensing device for granular materials, comprising a magazine having a pair

of sockets, each provided with an inlet opening from the magazine and an outlet opening, a measuring spindle rotatably fitted in each of said sockets and having a pocket shiftable, upon rotation of the spindle, from the inlet opening to the outlet opening, and a perforated spreader positioned to receive the material from one of said outlet openings and effect a spreading of the same. 70

10. A dispensing device for granular materials, comprising a magazine having a pair of vertical sockets, each provided with an inlet opening from the magazine and an outlet opening, the latter being positioned above the base of the device, a measuring 75 spindle rotatably fitted in each of said sockets and having a pocket shiftable, upon rotation of the spindle, from the inlet opening to the outlet opening, and a perforated spreader flaring outwardly and downwardly 80 from the device at the discharge end of one of the said outlet openings.

11. A dispensing device for granular materials, comprising a magazine having a vertical socket at one side thereof provided with an inlet opening from the magazine and an outlet opening, a measuring spindle rotatably fitted in said socket and having a pocket shiftable, upon rotation of the spindle, from the inlet opening to the outlet opening, a perforated spreader positioned to receive the material from the outlet opening and effect a spreading of the same, a rotatable stirring spindle within the magazine, a removable cover on the magazine having openings through which the upper ends of the measuring and stirring spindles project, and means for detachably locking said rotatable spindles in connection with the magazine. 100

105. 12. A dispensing device for granular materials, comprising a magazine having a vertical socket provided with an inlet opening from the magazine and an outlet opening, a measuring spindle rotatably fitted in said socket and having a pocket shiftable, upon rotation of the spindle, from the inlet opening to the outlet opening, said spindle being provided with an annular groove and a connecting groove extending to one end of the spindle, a fixed pin on the inner wall of the socket engaging the spindle within the annular groove therein to hold the spindle against longitudinal movement, and a removable cover for the magazine having an opening through which the upper end of the spindle extends and also having a lug engaging with a shoulder on the spindle to limit rotation of the latter and prevent the longitudinal groove therein being brought into registry with the locking pin on the inner wall of the socket. 110

115. 13. A dispensing device for granular materials, comprising a magazine having an outlet opening, a cover for the magazine 120

- having an opening, a rotatable spindle within the magazine having its upper end projecting through the opening in the cover as a means whereby it may be operated, 5 means for locking the spindle in connection with one of the magazine walls, and means carried by the spindle for engaging the cover and locking it in place on the magazine.
- 10 14. A dispensing device for granular materials, comprising a magazine having a socket provided with an inlet from the magazine and an outlet opening, a measuring spindle rotatably fitted in said socket and having a pocket shiftable, upon rotation of the spindle, from the inlet opening to the outlet opening, a stirring spindle within the magazine, a removable cover for the magazine having openings through which the 15 upper ends of the spindles extend, locking means loosely engaging each spindle and holding it in connection with the magazine, and locking means carried by one of the said spindles for engaging the top of the 20 cover and locking it in place on the magazine.
- 15 15. A dispensing device for granular materials, comprising a magazine having an outlet opening, a cover for the magazine 25 having an opening, a rotatable spindle within the magazine having its upper end projecting through the opening in the cover, means for locking said spindle in connection with one of the magazine walls, and means for locking the cover in place on the magazine comprising said spindle having an annular groove adjacent the top of the cover and a vertical groove extending from the top of the spindle to said annular 30 groove, a collar having an inwardly extending lug and adapted to be placed in locking connection with the spindle for engagement with the top of the cover by passing its said lug downwardly through the vertical groove in the spindle and then turning the same horizontally into the intersecting annular groove for locking connection with the spindle, and a locking member detachably located on the upper end of the spindle 35 with a part thereof extending into the said annular groove therein to prevent the projection on the locking collar being brought to releasing position opposite the vertical groove in the spindle.
- 40 16. A dispensing device for granular materials, comprising a magazine having a socket provided with an inlet from the magazine and an outlet opening, a measuring spindle rotatably fitted in said socket and having a pocket shiftable, upon rotation of the spindle, from the inlet opening to the outlet opening, a stirring spindle within the magazine, a removable cover for the magazine having openings through which the 45 upper ends of the spindles extend, locking 50 means loosely engaging the stirring spindle and holding it in connection with the magazine, and locking means carried by the stirring spindle for engaging the top of the cover and locking it in place on the magazine.
- 55 17. A dispensing device for granular materials comprising a magazine having a vertical socket at one side thereof provided with an inlet opening from the magazine and an outlet opening, a measuring spindle rotatably fitted in said socket and having a pocket shiftable, upon rotation of the spindle, from the inlet opening to the outlet opening, a removable cover for the magazine having an opening through which the upper end of the spindle extends, means engaging the spindle and holding it in its socket during a fixed movement of rotation, and means for confining the spindle to said 60 fixed movement of rotation.
- 65 18. A dispensing device for granular materials comprising a magazine having a socket provided with an inlet opening from the magazine and an outlet opening, a measuring spindle rotatably fitted in said socket and having a pocket shiftable, upon rotation of the spindle, from the inlet opening to the outlet opening, and locking means loosely engaging the spindle and holding it in connection with the magazine.
- 70 19. A dispensing device for granular materials comprising a magazine having a socket provided with an inlet opening from the magazine and an outlet opening, a spindle rotatably fitted in said socket and having a pocket shiftable, upon rotation of the spindle, from the inlet opening to the outlet opening, locking means loosely engaging the spindle and holding it in connection with the magazine, and a spreader for distributing the dispensed granular material.
- 75 20. A dispenser for granular materials having a magazine, a socket extending vertically within said magazine and having an inlet opening and an outlet opening, a spindle within said socket and having a pocket adapted upon rotation of said spindle to be brought into registry with said 80 openings to receive and discharge granular material, and a spreader for distributing the dispensed material.
- 85 21. A dispenser for granular materials having a magazine, a socket extending vertically within said magazine and having an inlet opening and an outlet opening, a cover for said magazine, a spindle within said socket and having a pocket adapted upon rotation of said spindle to be brought into registry with said openings to receive and discharge granular material, and a single means for confining the said spindle to a limited rotation and which also locks the spindle in the magazine to prevent untimely withdrawal therefrom.

22. A dispenser for granular materials comprising a magazine having an outlet opening adjacent its lower end, a removable cover for said magazine, a spindle within said magazine having a measuring pocket adapted, upon rotation of said spindle, to be disposed within said magazine to receive granular material therefrom and to

be brought into registry with said outlet opening to discharge the granular material in said pocket, and means for preventing the granular material within said magazine from flowing from said outlet opening during rotation of said spindle.

In testimony whereof I affix my signature.
CLIVE W. LANPHERE.
